United States Patent Office

Des. 223,441

Patented Apr. 18, 1972

23,441

BUILDING

John E. Holt, P.O. Box 264,
South Laguna, Calif. 92677

Filed Aug. 3, 1970, Ser. No. 24,263

Term of patent 14 years

Int. Cl. D25—03

U.S. Cl. D13—1

FIG. 1

FIG. 1 is a perspective view of a building unit embodying the invention;

FIGS. 2 and 4 are side views of the building of FIG. 1;

FIGS. 3 and 5 are views of the two ends of the building of FIG. 1; and

FIG. 6 is a view of the top of the building of FIG. 1.

I claim:

The ornamental design for a building, substantially as shown and described.
